UNITED STATES PATENT OFFICE

SAMUEL J. CAMPBELL, OF GREEN BAY, WISCONSIN, ASSIGNOR TO HUDSON-SHARP MACHINE COMPANY, A CORPORATION OF WISCONSIN

PAPER-WEB-FEEDING MACHINE

Application filed February 6, 1929. Serial No. 337,753.

This invention relates to improvements in paper web feeding machines.

The machine of the present invention is designed primarily for the purpose of feed-

5 ing a continuous strip or web of paper through embossing rollers and afterwards cutting off the embossed sections to form paper napkins, and in the exemplification of the invention shown and described the 10 machine is arranged as a duplicate machine for simultaneously feeding two strips or webs through the rollers and cutters.

In view of the fact that the same embossed design is repeatedly applied to the 15 paper web, and that the paper sections must be cut or severed between the embossed designs, it becomes important to provide adequate means for properly regulating the feed in such a way that the cutters will in each 20 instance act to sever the sections along the proper line so as to produce two napkins or the like on which the design is evenly and accurately centered.

Since the machine is designed to simultaneously operate on two webs or strips, the 25 requirement for accuracy is particularly important, and in the case of the present invention adequate means are provided for adjusting the webs individually and also for 30 properly adjusting the relation of one web to the other.

The machine is one which is designed to feed the webs in unison from two separate 35 rolls of paper in superposed relation through moving rolls, after which the webs are separated and fed individually over formers which longitudinally fold the webs prior to their passage through cutting rolls which serve to sever the webs into sections of proper 40 length.

In view of the fact that the webs pass in unison through the embossing rollers, and are afterwards separated and fed through different paths, it becomes necessary to provide 45 means for accurately adjusting the instrumentalities which control the paths of advance of the respective webs, and the present invention is directed to the provision of adequate means for this purpose.

50 The invention also relates to the general

structure of the machine as a whole, and to the general arrangement of the various instrumentalities for embossing, feeding, and cutting the paper.

In the drawings:

55 Figure 1 is a side elevation of the complete machine;

Fig. 2 is an end elevation thereof, taken on line 2—2 of Fig. 1;

Fig. 3 is a view taken on line 3—3 of Fig. 1;

Fig. 4 is a view taken on line 4—4 of Fig. 1;

Fig. 5 is a detail taken at right angles to Fig. 4, and showing the means for adjusting the elevation of the bars for guiding the paper webs;

Fig. 6 is a view taken on line 6—6 of Fig. 1; and

Fig. 7 is a view taken on line 7—7 of Fig. 6.

The machine as a whole comprises what may be termed an embossing section 10 and 70 a folding and cutting section 11 in close proximity to one another. The embossing section comprises a frame 12 provided with lower arms 13 and upper arms 14, which respectively support the paper rolls 15 and 16. 75 The paper webs run from the rolls in superposed relation to one another and pass between upper and lower embossing rolls 17 and 18 suitably mounted within journal boxes. The rolls may be adjusted with respect to one another by a screw adjusting device 19 of any suitable form which is adapted to regulate the pressure between the embossing rolls.

80 As shown, the upper roll 17 is mounted upon a power driven shaft 20, while the lower roll 18 is mounted upon a shaft 21 in superposed relation to one another, and the two paper webs are fed between the embossing rolls, the lower paper web being fed over an idle roll 22 which brings it immediately beneath the upper web.

85 The two webs, after being suitably embossed between the rolls 17 and 18, pass between a second set of embossing rolls 23 and 24 mounted upon shafts 25 and 26, the latter of which is power driven.

90 In order to rotate the two sets of embossing rolls at a uniform rate of speed, intermeshing gears 27 and 28 are mounted upon 100

the shafts 20 and 26 respectively, and the gear 27 is suitably driven by means of a sprocket chain 29 and gears 30 which derive power from a main power shaft 31.

5 The power driven rolls 17 and 24 are necessarily of the same size to emboss one napkin during a complete revolution, while the roll 18 may be of double size having a circumference of a length to act upon two succeeding napkins. The rolls of smaller size can be 10 built up to any desired surface area by the use of plates having the designs embossed thereon, which arrangement varies the capacity of the machine to operate on napkins of varying size. As illustrative of this principle, the rolls 18 and 24 are shown of different diameter, although rolls of the same diameter might be substituted.

15 Suitable screw means 32 are provided for 20 regulating the pressure upon the second set of embossed rolls. After leaving the second set of embossing rolls, the paper webs are separated and pass respectively under an upper cross bar 33 and a lower cross bar 34, best 25 illustrated in Figs. 4 and 5. These bars are individually adjustable at each end, in order to maintain the paper webs in a proper plane of travel to compensate against any tendency of either web to work laterally to its correct 30 path of advance.

At each end, the bars extend through a bracket 35 which is provided with a pair of vertical slots 36 and 37, through which the ends of the respective bars extend to permit 35 vertical adjustment thereof. In addition to the slots 36 and 37, each bracket is provided on each side with an inwardly extending flange 38 provided with a vertical slot 39.

40 The cross bars 33 and 34 are provided at each end with a laterally extending stud or post 40 which passes through the adjacent side slot, and each of these studs or posts is threaded to take a knurled nut 41, which may be screwed down to clamp the end of the rod 45 in proper vertically adjusted position. This arrangement enables the respective bars to be adjusted vertically to the desired degree, or to be slightly tilted at either end to compensate for inequalities in the feeding of the respective webs.

50 The lowermost web, after passing under the bar 34, now passes upwardly over a roller 42, and thence downwardly under a roller 43, which latter is journaled between swinging arms 44 which are journaled upon the axis of the roller 42, and are adapted to be clamped in properly adjusted relation by means of suitable clamping nuts 45 coacting with slotted segments 46.

60 The lower paper web, after passing under the roller 43, passes upwardly over a roller 47 and thence downwardly over an obliquely disposed former 48 which serves to longitudinally fold the paper web and direct it downwardly.

The upper web, after passing under the bar 33, passes upwardly and through a set of feeding rolls 49 and 50, the latter of which is power driven through the medium of a sprocket chain 51 deriving power through gearing 52 in train with the shaft 31. The upper web passes through additional rolls 53 and over a roll 54 immediately above a former 55 located in spaced relation to the former 48, so that the upper web will be folded and travel downwardly in the same plane as the web first referred to.

65 In order to permit adjustment of the power driven roller 50, with respect to the sprocket chain 51, the arrangement shown in Figs. 6 and 7 is provided. The sprocket chain passes around a sprocket wheel 56, which is formed integral with a disk 57 provided with outwardly extending bolts 58 which pass through circumferentially elongated slots 59 formed in a disk 60 rigidly secured to the end of a shaft 61 upon which the roller 50 is mounted.

70 By loosening the bolts, the sprocket wheel can be turned freely to the extent necessary to secure a proper adjustment between the sprocket chain and the roller. This enables the upper web to be adjusted back and forth within adequate limits to secure proper feeding relation between the upper and lower webs, in addition to which the lower web 95 may be adjusted by swinging the arms 44 which carry the roller 43, so that the distance between the roller 43 and the roller 47 may be varied, thus varying the length of travel of the lower web between the embossing rollers and the roller 47.

75 After passing down over the formers 48 and 55, the longitudinally folded webs pass down through cutting and folding mechanisms in all respects like those shown in Campbell Patent No. 1,666,086, issued April 17, 1928. The special details of these mechanisms form no part of the present invention, and it is not deemed necessary to describe them in detail. It suffices to say that they include cross folding rollers *a* and *b* (the former of which acts as a cutting roller), co-operating with a folder blade (not shown) which acts against the once folded and severed web sections and carries them into the bite of the rollers *a*—*b* which complete the cross fold and deliver the twice folded napkins to carriers *c* which carry them down to the trough *d* in which they are stacked, all as shown in detail in the patent referred to.

80 These mechanisms serve to simultaneously cut both of the once folded webs into sections of the proper length and to cross fold the cut sections so that the embossed napkins are delivered twice folded from the machine. These mechanisms, however, must be synchronized with the embossing and feeding mechanisms, and for this purpose the driving sprocket chain 62 passes over a sprocket 63 which is adjusted through the provision of 120

discs 64 in all respects like those previously described.

In operation, the superposed upper and lower webs will pass between the first and second set of embossing rollers to receive the desired impression, after which the webs will be separated and pass individually under the cross bars 33 and 34, which are adjustable to insure accurate directing of the respective webs, after which the webs pass through separate paths and over the respective formers to the cutting rollers. Since cutting means are employed, it is essential that the two webs reach the cutting point in accurate alignment with one another, in order that the cut may occur between the embossed patterns. This requires that the duplicate patterns on the respective webs reach the cutting point abreast one another; and to insure accuracy in this adjustment, the length of the feeding path for the lower web may be adjusted by the means heretofore described, and in addition to this the feeding of the upper web may be adjusted by properly setting the roller 50 with respect to the power transmission derived from the shaft 31. In like manner, the cutting rolls may be adjusted in accurate relation to the source of power, and these adjustments are quite important in view of the fact that all portions of the mechanism are driven from the same shaft 31, so that a proper synchronizing of the embossing, feeding and cutting instrumentalities is required.

It will be understood, however, that it is not the intention to limit the invention strictly to the employment of all of the adjustments described, although for convenience and accuracy in feeding all are desirable.

Although the invention has been described with particularity as to detail, it is not the intention to limit the invention strictly to the features shown and described, since modifications thereof may be made without departing from the spirit of the invention.

I claim:

1. In mechanism of the class described, the combination of means for supporting a pair of paper rolls, means for feeding the webs coming from the rolls in superposed relation to one another, means for embossing the superposed webs, means for separating the webs and feeding the same individually, means for varying the length of the feeding path of one of the webs, means for bringing the two webs into relation abreast of one another, and cutting devices for simultaneously severing corresponding sections from the two webs.

2. In mechanism of the class described, the combination of means for supporting a pair of paper rolls, means for feeding the webs coming from the rolls in superposed relation to one another, means for embossing the superposed webs, means for feeding the same

individually, means for varying the length of the feeding path of one of the webs, means for bringing the two webs into relation abreast of one another, cutting devices for simultaneously severing corresponding sections from the two webs, the feeding means including guide bars beyond the embossing means for separating the previously superposed webs, and means for individually adjusting the angularity of the guide bars.

3. In mechanism of the class described, the combination of means for supporting a pair of paper rolls, means for feeding the webs coming from the rolls in superposed relation to one another, means for embossing the superposed webs, means for separating the webs and feeding the same individually, means for varying the length of the feeding path of one of the webs, means for bringing the two webs into relation abreast of one another, cutting devices for simultaneously severing corresponding sections from the two webs, means for driving the embossing, feeding, and cutting instrumentalities from a common source of power, and adjusting means for securing synchronization between the driving of the several instrumentalities.

4. In mechanism of the class described, the combination of means for supporting a pair of paper rolls, means for feeding the webs coming from the rolls in superposed relation to one another, means for embossing the superposed webs, means for feeding the same individually, means for varying the length of the feeding path of one of the webs, means for bringing the two webs into relation abreast of one another, cutting devices for simultaneously severing corresponding sections from the two webs, the feeding means including guide bars beyond the embossing means for separating the previously superposed webs, means for individually adjusting the angularity of the guide bars, means for driving the embossing, feeding, and cutting instrumentalities from a common source of power, and adjusting means for securing synchronization between the driving of the several instrumentalities.

5. In mechanism of the class described, the combination of means for supporting a pair of paper rolls, means for directing webs derived from said rolls into superposed relation to one another, embossing rolls through which the superposed webs are fed, means for separating the superposed webs and directing each through a separate feeding path, a former for each of the webs, adapted to longitudinally fold the web, the two formers being positioned to direct the folded webs into abreast relationship to one another, and means for severing correspondingly embossed sections from the respective webs.

6. In mechanism of the class described, the combination of means for supporting a pair of paper rolls, means for directing webs de-

- rived from said rolls into superposed relation to one another, embossing rolls through which the superposed webs are fed, means for separating the superposed webs and directing each through a separate feeding path, a former for each of the webs, adapted to longitudinally fold the web, the two formers being positioned to direct the folded webs into abreast relationship to one another, 5 means for severing correspondingly embossed sections from the respective webs, and means for varying the length of the feeding path of one of the webs between the embossing rolls and the former for said web.
- 10 7. In mechanism of the class described, the combination of means for supporting a pair of paper rolls, means for directing webs derived from said rolls into superposed relation to one another, embossing rolls through 15 which the superposed webs are fed, means for separating the superposed webs and directing each through a separate feeding path, a former for each of the webs, adapted to longitudinally fold the web, the two formers being 20 positioned to direct the folded webs into abreast relationship to one another, means for severing correspondingly embossed sections from the respective webs, means for driving the embossing rolls, the feeding 25 means, and the cutting means from a common source of power, and means for synchronizing the driving of said respective instrumentalities. 30
8. In mechanism of the class described, the 35 combination of means for supporting a pair of paper rolls, means for directing webs derived from said rolls into superposed relation to one another, embossing rolls through which the superposed webs are fed, means 40 for separating the superposed webs and directing each through a separate feeding path, a former for each of the webs, adapted to longitudinally fold the web, the two formers being positioned to direct the folded webs 45 into abreast relationship to one another, means for severing correspondingly embossed sections from the respective webs, means for varying the length of the feeding path of one of the webs between the embossing rolls and the former for said web, means 50 for driving the embossing rolls, the feeding means, and the cutting means from a common source of power, and means for synchronizing the driving of said respective instrumentalities. 55
9. In a machine of the class described, the 60 combination of rolls adapted to feed superposed webs between the rolls, cross bars adjacent to said rolls, adapted to separate the previously superposed webs, and means for adjusting the angularity of said bars to compensate for any inaccuracies in feeding. 65
10. In mechanism of the class described, the combination of means for individually feeding two separate sets of webs in diverse 70 paths of movement, said means including a roll around which one of the webs is passed, and swinging arms between which said roll is mounted, and means for locking said arms in adjusted relation to vary the length of the feeding path of the web passing around said roll. 75
- In witness that I claim the foregoing I have hereunto subscribed my name this 31st day of January, 1929. 80
